UNITED STATES PATENT OFFICE

114,786

DESIGN FOR A COMBINED SOLE AND HEEL

Adelbert Cushing Cutler, Braintree, Mass., assignor to Alfred Hale Rubber Company, Quincy, Mass., a corporation of Massachusetts

Application June 24, 1938, Serial No. 78,026

Term of patent 14 years

To all whom it may concern:

Be it known that I, Adelbert Cushing Cutler, a citizen of the United States, residing at Braintree, in the county of Norfolk and Commonwealth of Massachusetts, have invented a new, original, and ornamental Design for a Combined Sole and Heel, of which the following is a specification, reference being had to the accompanying drawing, forming part thereof, wherein:

Fig. 1 is a bottom plan view of a combined sole and heel showing my new design; and

Fig. 2 is a side elevational view of the same. The characteristic features of my design re-

side in a "tap" sole and base, wherein the "tap" sole has a creped surface, a color contrasting with that of the exposed shank face and the edges of the base, and a triangularly-configured shank edge portion having substantial thickness and an apex occurring substantially coincidentally with the longitudinal medial axis of said sole.

I claim:

The ornamental design for a combined sole and heel, substantially as shown and described.

ADELBERT CUSHING CUTLER.
